BOTTLE FILLING VALVE

James Kantor, Chicago, Ill., assignor to The Liquid Carbonic Corporation, Chicago, Ill., a corporation of Delaware

Application March 3, 1930. Serial No. 432,721

5 Claims. (Cl. 226—111)

My invention relates to improvements in bottle filling machines and more particularly to the filler valve for said machines.

It is one of the objects of my invention to provide a means for controlling the supply of liquid delivered through said valve.

For the purpose of disclosing my invention, I have illustrated one embodiment thereof in the accompanying drawing, in which:

10 Fig. 1 is a longitudinal sectional view of a filler valve embodying my invention; and

Fig. 2 is a transverse section on the line 2—2 of Fig. 1.

In the structure illustrated, I provide a base 1 by which the valve structure may be supported from the filling tank (not shown) and which is provided with a series of ports hereinafter more fully described. This base supports a tubular casing 2 which is in turn screw threaded at its

20 top to a nipple 3 in turn screwed into a socket 4 in the base 1. Telescoping this tubular casing is a second casing 5, the downward movement of which is limited by a ring 6, threaded on the top of the casing 5 and adapted to engage, when

25 the casing 5 is in its lowermost position, an annular flange 7 on the casing 2. The casing 5 near its lower end is provided with a head 8 resting on a shoulder 9 within the casing, and interposed between this head and an inturned flange 10

30 on the nipple 3 is a coiled spring 11 which tends to move the casing 5 to its lowermost position.

A sealing head 12 is threaded into the lower end of the casing 5 and carries at its bottom a gasket 13 which is counter-sunk in the head.

35 This sealing head 12 also supports at its lower end a bottle guide neck 14 which receives the neck of the bottle when the bottle is raised to filling position. The head 12 also carries on its upper end a nut 15 threaded into the head against

40 a packing gasket 16, and provided with a tubular neck 17 which extends upwardly through the head 8.

Arranged within the casing formed by the two casing tubes 2 and 5 are the water tube 18, the counter-pressure tube 19 and the snifter tube

45 20. These tubes are arranged one within the other and are so mounted that none communicates with the other. The water filling tube 18, at its upper end, is screw threaded into a socket

50 21 in the base 1 and communicates through a port 22 with a chamber 23 which in turn is connected with the water delivery pipe 24 leading from the filling tank. This chamber has a series of passages 25 extending around an interior ball

55 casing 26 to the top 27 of the chamber. The ball

chamber 26 communicates with the top 27 of the chamber 23 through a port 28 and is provided with a ball valve 29 adapted, in event of a sudden rush of water occasioned, for example, when a cracked bottle operates the filler valve, to close 60 this port. This ball chamber 26 communicates by a passage 30 with the supply pipe 24. For controlling the quantity of water supplied through the chamber 23, I provide a valve plate formed of two segments 31 and 32 adapted, by 65 the rotation of the plate, to cover, a greater or less number of the openings 25. This valve plate is secured at the bottom end of a stem 33 extending through the top of the casing and provided with a manipulating handle 34. A coiled 70 spring 35 interposed between a collar 36 and the valve plate holds the plate firmly seated in position.

The port 22 is controlled by a valve 37, normally closed by a coiled spring 38 and provided 75 with an opening stem 39 which projects below the bottom of the base 1.

The counter-pressure tube 19 is screw threaded into a block 40 mounted in the base 10 and communicates through a port 41 and a port 42 with 80 the chamber 43, which chamber has passages 44 extending around a valve casing 45 to the top 46 of the chamber. This valve casing 45 communicates through a port 47 with the top 46 of the chamber and is provided with a ball 85 valve 48 which, in event of a sudden rush of gas through the port 49 will be raised to close the port 47 thereby cutting down the amount of gas passing through the valve 51. This ball valve casing 45 communicates by the port 49 with the 90 gas supply pipe 50.

The port 42 is controlled by a valve 51 normally held seated by a coiled spring 52 and provided with an opening stem 53 which, it will be noted, is longer than the stem 39. 95

The snifter tube 20 sockets in a nipple 54 maintained in position by the annular flange 10, and communicates through a suitable port, not shown, with a snifter valve communicating with the atmosphere.

The lower end of the water supply tube is controlled by a pear shaped valve 55, the upper end of which is hollow and adapted to telescope the lower end of the water supply tube. This hollow portion of the valve is provided with discharge openings 56 at diametrically opposite points in the side through which when the valve is moved to opened position the water from the tube 18 discharges. This valve is mounted upon the lower end of a control rod 57 which extends 110

through the supply tube and upwardly through the base 1 to the top thereof, the valve being opened by a suitable lever (not shown). The upper end of the rod is provided with a pair of lock nuts 58 and the valve is maintained in its closed position by a coiled spring 59 interposed between one of the lock nuts and the base 10.

In operation, when a bottle is raised beneath the filling valve, the neck comes in contact with the gasket 13 raising the sleeve 5 and at the same time permitting the water tube, counter-pressure tube and the snifter tube to project into the bottle. The raising of the sleeve 5 first contacts the ring 6 with the valve stem 53 opening the valve 51 and permitting the admission of counter-pressure gas into the bottle. The continued upward movement of the bottle causes the ring 6 to eventually engage the valve stem 39 thereby opening the valve 37 and allowing the carbonated water from the filling tank to flow into the water tube. At the same time that the valve 37 is opened the valve 55 is opened thus permitting the water to flow into the bottle. As the bottle is being filled with water the counter-pressure gas and the air in the bottle passes back through the counter-pressure tube 19 back into the tank. The lowering of the bottle first closes the carbonated water supply valve and then closes the counter-pressure valve.

For controlling the quantity of water delivered through the water supply tube the valve plates 31 and 32 may be manipulated to open a greater or less number of the openings 25, whereby the quantity of water flowing through the water supply tube may be nicely adjusted.

I claim the following:

1. In a bottle-filling head, in combination, a water supply tube for insertion into the bottle, a bottle controlled valve for controlling the passage of water through said water supply tube, a check valve associated with said bottle-controlled valve and constructed to automatically prevent abnormal flow of water through said supply tube and a

valve for controlling the degree of flow of water through said water supply tube.

2. In a bottle filling head, in combination, a water supply tube for insertion in the bottle, a bottle controlled valve for controlling the passage of water through said water supply tube, a check valve associated with said bottle-controlled valve constructed to automatically prevent abnormal flow of water through said supply tube and a valve for controlling the degree of flow of water through said water controlling valve.

3. In a bottle filling head, in combination, a counter-pressure tube and a water supply tube for insertion in a bottle, a bottle controlled valve for controlling the flow through said counter-pressure tube, a bottle controlled valve for controlling the flow through said water supply tube, a check valve associated with said water supply valve and having passages therearound for the passage of the water and controllable means for closing some of said passages.

4. In a bottle filling head, in combination, a counter-pressure tube and a water supply tube for insertion into the bottle, a bottle controlled valve for controlling the flow through said counter-pressure tube, a bottle controlled valve for controlling the flow through said water supply tube, a check valve casing associated with said water supply valve, said water supply valve having passages therearound, and controllable means for closing said passages.

5. In a bottle filling head, in combination, a water supply tube for insertion into said bottle, a bottle controlled valve for controlling the flow through said water supply tube, a ball valve associated with said water supply valve through which the water passes to said water supply valve, and having passages therearound, and controlling means for controlling the number of passages through which the water passes to said water supply valve.
